UNITED STATES PATENT OFFICE

SPENCER C. CARY, OF BROOKLYN, NEW YORK, ASSIGNEE, BY MESNE ASSIGNMENTS, TO THE GERRARD COMPANY, INC., OF SAN FRANCISCO, CALIFORNIA, A CORPORATION OF DELAWARE

WIRE-TENSION MECHANISM

Application filed May 2, 1924. Serial No. 710,695.

This invention is a means for placing under tension a wire in the operation of banding a box, package, or other shipping container.

Said tension mechanism is useful in connection with package banding machines generally, and more particularly is it adapted to be used as a part of package banding machines of the portable type.

One object is to place under tension a band by pulling thereon in two directions, whereby the slack is taken up quickly and the band is drawn so tightly around the package that it is not displaceable therefrom in the ordinary handling or use of said package. In fact, the band compresses the package and thus adds materially to the stability of said package. Further, the band is embedded in the corners of the package so as to be interlocked therewith, and thus retained by the package itself from slipping off should the package become decreased in cross sectional area due to shrinkage of the cheap material, usually wood, composing said package.

A further object is to utilize bands of predetermined lengths, usually composed of wire, and adapted for the expeditious application to packages, which packages may be uniform as to size and shape, as is the case in large packing and shipping establishments. Said bands may, however, vary in length according to the sizes of different packages to be bound with wire or other metal strapping.

In a practical embodiment of my tension mechanism, it includes a plurality of heads rotatable on a common axis, each of said pulling heads being provided with a band gripping device and one of said heads being provided, also with a band stop. Said stop operates to arrest the movement of a band when the end portion thereof is introduced into the machine for engagement with said band-pulling device.

The band gripping device on one head embodies a plurality of members positioned in cooperative relation to each other and adapted for mutual engagement with a band for holding the same securely and to prevent it from slipping under the pull of the head. Said members are usually provided with

teeth on the faces which are opposed one to the other, and said members are in the form of movable grippers each of which is pivoted for movement relatively to the other, and one or both of said pivoted members or grippers being spring actuated. The pulling device is adapted for engagement with bands of different kinds, such as plain round wire bands or plain flat wire bands, or shouldered wire bands, with either of which forms of bands the co-operating grippers are adapted to engage so securely that no slipping occurs under the strain applied to the band for pulling it tightly around the package.

The pivoted grippers are so related that the serrated faces are inclined relatively to produce a tapering space between said faces, which tapering space at the end into which the band is introduced is of a width exceeding the diameter of the wire, whereby a wire band is thrust easily into engagement with the grippers, the latter being yieldable to the wire when moved in a direction to introduce said wire into the machine.

It is desirable in a tension device of this character to limit the insertion of the band with respect to the members or grippers on the rotatable pulling head, and more particularly is it desirable to deflect the end portion of the band relatively to the stopping member when the pulling head is turned or rotated in a backward direction for restoring the pulling head and the grippers to normal position. The stopping device employed in the present instance is a piece attached to the pulling head in a position to lie in the path of the band and adapted for contact with the extremity of said band when the latter is thrust between the grippers. Such a stopping device is useful for determining the extent to which a shouldered band may be thrust between the grippers in order that said grippers will engage properly with the shoulder of the band, but it will be understood, of course, that the stopping device is useful also for arresting the introductory movement of plain round wire bands and plain flat wire bands.

My invention consists, further, in a novel form of the other of said two pulling heads

adapted for the fixed attachment thereto of a binder, either plain round wire or plain flat wire, said head having a notch into which an end portion of the band may be bent by hand. Said head carries a dog positioned adjacent to the notch therein, which dog is pivoted to the head for gripping engagement with the band upon the rotative movement of the head in one direction, whereby the dog and the notched head co-operate in retaining the band from slipping when tension is applied by said rotative movement of the head. Upon the rotative movement of the head in an opposite direction, i. e. in a direction to return the head to normal position, the dog is released automatically from the band, and this release is occasioned by contact of the dog with a member in the form of a stud or post which is positioned in the path of the dog for contact therewith.

The tension mechanism includes means for directing the opposite end portions of a band into positions for engagement with the respective pulling heads. Said tension mechanism includes, also, means for retaining the band under the tension or strain applied thereto so that the tension mechanism as a whole may be returned to normal position while said band remains under tension, where- by a lever of the tension means may be employed for holding the machine steadily in position for the performance by other mechanism of the tying machine of the operations of tying the end portions of a looped band and of cutting from the looped band the surplus material, the cutting operations being performed at points close to the tie or twist resulting from the tying operation.

Other functions and advantages of the invention will appear from the following description taken in connection with the drawings, wherein—

Figure 1 is a plan view of a tying machine with my tension mechanism associated with other parts, comprising the tying machine.

Figure 2 is an elevation looking at the left hand side of the machine, with a shouldered band thrust into engagement with the grippers of the left hand pulling head, the latter being shown in a normal position.

Figure 3 is a diagrammatic view of the parts of the tension mechanism illustrated in Figure 2, illustrating in full lines the left hand pulling head rotated through an arc of about 90°, while the dotted lines show said pulling head reversed and returned to normal position with the band under tension and with the extremity of said band projected beyond the gripping mechanism of said pulling head.

Figure 4 is an elevation of the machine looking toward the right hand pulling head, with the latter in normal position.

Figure 5 is a diagrammatic view of the right hand pulling head rotated through an arc of

about 90° and showing in dotted lines the pulling head returned to normal position and with the bent end of the band projected to a position free from the pulling head.

Figure 6 is approximately a vertical section on the line 6—6 of Figure 4.

Figure 7 is a horizontal section on the line 7—7 of Figure 6.

Figure 8 is a detail perspective view of one of the anchor blocks for a direction sheave 75 of the tension mechanism.

Figure 9 is a detail view of the band stopping device adapted to be carried by the left hand pulling head.

Figure 10 is a detail section of one of the band holding dogs on the line 10—10 of Figure 7.

Figure 11 is a fragmentary detail of the twisting means used in the tying machine.

Figure 12 is a perspective view of a completed loop with its end portions tied by twisting the same and cutting off the ends.

Figure 13 is a diagrammatic view of the left hand pulling head showing the band gripper in normal position ready to receive 90 an end portion of the band.

Figure 14 is a similar view of the left hand pulling head illustrating the gripping means in engagement with a plain round wire.

A tying machine with my band tensioning 95 mechanism is illustrated in Figures 1 to 7, inclusive, of the drawings, wherein A is the machine frame having a base plate *a* and bearings *b* for a horizontal shaft B. The base plate is of suitable dimensions for the accommodation of the several working parts of the machine, said base plate having a forwardly extending member *c* with an inclined top face *c'*, see Figures 2 and 4, adapted to serve as a directing member by which a band, usually a round wire, is adapted to be placed by hand into certain horizontal slots, the positions of which are indicated at *d* provided in the forward ends of bearings *b*, see Figure 7. The bearings *b* of the frame work 110 are parallel, as shown in Figures 1 and 7, so as to leave a space between them for the reception of the pillar plates C C, the forward ends of which are provided with recesses adapted to serve as bearings for the 115 journals *d'* of a twister pinion D, said pinion and its journals being provided with a longitudinal slot *d''* which extends radially with respect to the pinion and opens through the periphery thereof, see Figures 11 and 12. Against the outer faces of the bearing members *b* are positioned shear plates E E, one on each side of the twister pinion D, said shear plates having slots *e* which are in alignment horizontally with the slots *d* of bearings *b* and with the slot *d''* of twister pinion D.

F F are anchor blocks, one of which is shown in detail in Figure 8. Said anchor blocks are fitted against the outer sides of 130

the shear plates E E, respectively, and G are bolts which pass through the anchor blocks F, the shear plates E, bearings b, and are threaded into the pillar plates C, see Figure 7, whereby the anchor blocks, the shear plates and the pillar plates are drawn into solid engagement with the bearings b b so as to be held immovably by clamping engagement with bearings b of frame A.

5 Said anchor blocks are each composed of a single piece slotted at f and recessed at g, said recesses g in the respective anchor blocks being adapted to receive the heads g' of the clamping bolts G, see Figure 7. Each anchor block is provided with a projecting lug h performing the function of a guide for the band, whereas the slot f of said anchor block houses a direction sheave H, the same being mounted for rotation freely on a vertical 15 axis h' supported by the anchor block. There are two direction sheaves, one on either side of the twister D, and these sheaves are positioned in such relation to the slots e d d' that a band is adapted to be passed 20 through said slots and to contact frictionally with the edge portions of said sheaves.

The shaft B affords a support for a large gear I, the hub of which is mounted loosely on the shaft between the bearings b b. Said 25 gear is in mesh with the twister pinion D, and said gear is provided with an offstanding socket member i' in which is fixedly secured a lever I' having a hand grip i'. A curved guard plate I² is positioned over the 30 gear I and its ends are secured fixedly to the bearings b, b.

J J are cutter blades or knives positioned in shearing relation to the slotted shear plates E E, one cutter being at either side of the 35 twister pinion, and said cutters being pivoted by pins j to the shear plates for rocking movement relatively thereto. The cutters are provided with cutting edges so fashioned that they operate on the separate lengths or 40 end portions of the looped band. The cutters are held in position by springs j' anchored at j' at one end on the machine frame, and said cutters are in the path of cam studs j² carried by the gear I and extending outwardly therefrom, whereby the cam studs are 45 adapted to ride against the cutters for imparting movement thereto in timed relation to the action of the twister upon the end portions of a looped band.

50 The tension mechanism for the band embodies a plurality of pulling heads K, L, and an operating lever O. Said pulling heads are mounted on the shaft B, at or near the opposite ends thereof, said heads being made fast in a desired manner with said shaft, as by set screws, whereby the heads and the shaft are rotatable as a unit. The heads K, L, are constructed for the attachment of the 55 opposite end portions of a band for pulling

on said band in two directions so as to quickly take up the slack in the band after it shall have been formed by manual manipulation into a loop which may be said to encircle the object, said heads operating to also pull the 70 band for placing thereon any degree of tension determined by the operator and which is or must be that tension required to embed the band into the corners of the package, 75 whereby two important functions are attained; first, the band is applied tightly upon the package with a view to compressing it, more or less, so that the band adds materially to the stability of the package, and, second, the band and the package are interlocked by 80 embedding said band into the corners of the package, thus preventing the band from sliding off the package should the wood shrink to such an extent as to loosen the band around the package. 85

The head K is provided with a member in the form of a web k extending outwardly therefrom and with a sleeve k', into which sleeve is secured an end of lever arm O, the outer end of which lever arm is provided 90 with a hand grip o.

On the member k of the head K are mounted the members of a band-gripping device which is engageable with a plain round wire as in Figure 14, or with a shouldered band, 95 as in Figures 2, 3 and 7. Said band-gripper embodies a plurality of dogs P P' separately pivoted at p p' whereby the dogs are movable independently of each other. The dogs are shown as being positioned in facing relation, and the opposing edges of said dogs are roughened, toothed or serrated at p². The dog P in the normal position of the pulling head K is above the dog P'. Said dog P is under the influence or control of a spring p³, 100 whereas the dog P' is actuated by gravity and its play or movement is limited by stop pins p⁴ attached to member k of the pulling head K at points on opposite sides of said pivoted dog P'. 110

The dogs are yieldable to the end thrust of a band when the latter is forced in a direction between the dogs, but a pull on the band in the opposite direction is resisted by the dogs, the serrated faces of which act to grip the band so firmly that a movement of the band relative to dogs in one direction is resisted or in fact precluded. To facilitate the insertion of the band when used either as a plain round wire or as a shouldered wire, I 120 position the dogs P P' so that the serrated faces p² are relatively inclined, with the result that a tapering space is formed between the faces p². This space is sufficiently wide at one end for the wire to enter freely, the width of the space exceeding the diameter of the wire. As the wire is shoved into position by an endwise movement, the end of the wire contacts the serrated faces of the dogs, and the later turn on the pivots p' p², the dogs 125 130

being yieldable to the insertion of the wire when moved in one direction.

In connection with the head K and the band gripper carried thereby, I find it desirable to employ a stopping device Q operating to arrest the forward movement of the band when it is introduced into the machine, so that said band will be engaged automatically with the band gripper of head K. Said device is useful, particularly, in determining the movement of that form of band having a flattened section α and shoulders α' , as shown in Figures 2, 3 and 7, to the end that the introduction of the band between the gripping dogs P P' is arrested by stop Q at such a period of its introductory movement that the noses of the dogs will engage rearwardly of the band shoulders, see Figure 2, whereby the dogs have engagement with the band not only by reason of the serrated faces becoming embedded, more or less, into the band, but the nose of each dog lodges back of a shoulder to the end that the dogs so securely grip the band that no slipping of the band can take place regardless of the amount of pull or strain applied by the pulling head to the band. The stopping device in a practical form of construction is shown in detail in Figure 9, and applied in an operative position in Figures 2, 3 and 7 of the drawings. As there shown, the stopping device Q is in the form of a plate with a curved or beveled edge q, and it is provided with a flange q^2 at one edge and with a thickened lug q^2 at the opposite edge. This lug is fitted against the edge of member k on the pulling head of the plate to lie in the path of a band when the latter is thrust between the dogs P P', see Figures 2, 3 and 7, the flange q' and lug q^2 being on opposite sides of the band end. The stopping device is fixedly attached to the head K by screws r adapted for insertion through apertures r' provided in the lug q^2 , said screws being threaded in female threaded openings provided in member k of said head K, see Figure 7. The stopping device is thus attached fixedly to the head K for rotative movement therewith, and said device is thus at all times in an operative position relatively to the gripping dogs P P' to arrest the introductory insertion of a band, whereby the dogs are adapted for engagement with a shouldered band rearwardly of the shoulders thereof. The utility of the flange q' on one side of the stop Q is to limit the sidewise movement of the free end of the band with respect to the dogs when said band is bent around the adjacent direction sheave H in the operation of training the band within the slotted front part of the machine and around the package. The utility of the beveled or curved face q of said stop Q is to permit the extremity of the band to slip or ride over said face q when the pulling head is reversed after

placing tension on the band and while said band is held under tension by certain grippers to be presently described.

The other pulling head L (on the right hand end of shaft B) is shown more particularly in Figures 1, 4, 5 and 7 of the drawings, said head L being a single casting provided with a protruding member l, said head being provided also with a notch l' extending through the curved edge and opening through a side face of the head, see Figures 4 and 5, whereby an end portion of the band is adapted to pass part way around the curved face of the head and is bent by hand into the notch l' in order to attach said end of the band to the pulling head L. To prevent the attached end of the band from slipping relatively to the head in the operation of placing tension on the band, I provide a single gripper R which is mounted on the member l of the head L for movement therewith, said gripper R being in co-operative relation to the curved face of head L. The gripper is mounted pivotally on the head L by a stud or pin s, and said gripper is provided with teeth or serrations s' for non-slipping engagement with the band. The gripper R coacts with the curved face of the head L to securely retain the band during the operation of turning said head and gripper for placing tension on the band, but upon the reverse movement of the head and gripper to return the tension means to normal position, the band end is free to slide with respect to the head L and gripper R, see dotted lines in Figure 5, the band being retained under tension by certain holding means. The gripper R is released from the band upon the return of the head L to normal by a post or stud R' extending upwardly from a base a and positioned in the path of the gripper, said post or stud R' being in such relation to the gripper R that the outer edge of the gripper will contact with the post at a point which will turn the gripper on its pivot s and thus withdraw the serrated face s' of said gripper from engagement with the band, whereby said end portion of the band when severed from the loop may be removed from the machine with facility.

In my invention, the pulling heads K L and shaft B are rotated through an arc by a forward pull on lever O, said heads pulling on the band in opposite directions for taking up slack therein and placing tension on the band to a degree determined by the workman. During the operation of tensioning the band, it is held from slackening or relaxation by band holders in the form of dogs T U, one on each anchor block F, said holding dogs being engageable with end portions of the band at points intermediate the pulling heads K L and the twister pinion D. The dogs T U retain the looped portion of the band against relaxation of the tension

placed thereon, and thus the tension mechanism (heads K L and lever O) may be returned to normal position without relaxing tension on the looped band, and twister pinion C is adapted to be rotated for twisting together the terminal portions of the loop while said looped band is under tension. This method of holding the band under tension independently of the action of the tension mechanism permits the heads K L and lever O to be turned backwardly for the parts to occupy a normal position during the subsequent operation of the twister and the cutters.

This is advantageous for the reason that it enables the workman to apply pressure with the hand to the lever O for holding the machine steadily in place upon the package while said workman is engaged in pulling forwardly on the lever I' with the other hand, as a result of which the workman is able to use both hands, one for operating the tension means and the other for operating the twisting means. The holding dog T is positioned alongside one anchor block F below the lip h and adjacent the pulling head K, see Figures 2, 3 and 10. Said dog is loosely mounted on a stud t attached to block F, and it is provided with a serrated face t' and with a pin t², the latter extending in a recess t³ of anchor block F, so as to be engaged by a spring t⁴ which acts on the pin for turning the dog in a direction to move the serrated face t' into co-operative relation to the under face of the lip h on the anchor block, whereby dog T is positioned for gripping engagement with that part of the band leading to the pulling head K.

The other band holding dog U is pivoted at u to the opposite anchor block F, and like dog T, said dog U has a serrated face u' and a pin u² extending into a recess of block F for engagement with a spring similar to spring t⁴, whereby the dog is moved for its serrated face to co-operate with the lip h of said other anchor block and the dog is thus adapted to engage that part of the band leading to pulling head L.

The levers I', O for the twisting means and the tension means are positioned in side by side relation so that they may be turned rearwardly of the operating mechanisms of the machine as in Figures 1, 2 and 4. Each lever I' or O is provided with a short pendent post V, see Figures 2 and 4, adapted to rest upon the package, and to steady the machine in the operation thereof.

The operation of the machine will be apparent from the foregoing description, but it may be summarized as follows: With the parts in normal position shown by full lines in Figures 1, 2, 4, 6 and 7, and with the machine resting upon a package Z, a wire band of the proper length to go around a package is selected by the operator, and said band

is connected with the machine and looped around the package preliminarily to operating said machine for placing tension on the band, and twisting its ends together before cutting surplus material from the looped band. In the drawings, I have shown a shouldered band X used in conjunction with the machine for binding or strapping the package, said band having near one end thereof a flattened section x and a plurality of shoulders x', but in Figure 14, I have shown my machine adapted for the use of a plain non-shouldered band consisting of a piece of round straight wire, it being optional with the workman to use shouldered wire or plain wire, either round or flat, as desired.

The workmen inserts the shouldered or flattened end portion of the wire below the lip h and over the holding dog T at the left side of the machine, and thrusts the band endwise so it passes between gripper dogs K L, this endwise movement being continued until the extremity of the band comes into contact with stop Q. Said gripping dogs thus engage with the flattened and shouldered band, as in Figures 2 and 3 for effecting the secure attachment of one end of the band to the pulling head K. The operator now bends the band around the left sheave H, the lip g' of stop Q confining the gripped end of the band against sidewise movement relatively to dogs K, L, and in thus bending the band around sheave H the operator places the band in the slots e, d, d², of the shear plates E, the bearings b, and the twister C. That part of the band which emerges from the machine is bent by the workman around the package Z, and the other end portion of the band is now positioned again within the slots e, d, d², whereupon the unattached end of the band is bent around the other sheave H, placed over the dog U and under lip h of the other anchor block, bent part way around pulling head L, into engagement with the gripper dog R and finally the extremity is bent into notch l' of pulling head L. The band is thus looped to encircle the package, see Figure 1, the ends thereof are engaged with the pulling heads K L, and two lengths of the band are positioned in side by side relation within the slots e d d², see Figure 7.

The wire is manipulated prior to the operation of the machine, and this is now done in the following way: The operator grasps the grip i² of lever I' and presses downwardly thereon with one hand to steady the machine, while with the other hand he grasps the lever O and pulls upwardly and forwardly thereon, thus imparting motion to shaft B and turning the pulling heads K L in an arc of a circle. The heads pull on the wire or band simultaneously by straining the same in opposite directions, head K pulling to the left and head L to the right, thus quickly taking up the slack in the band and placing the re-

quired tension thereon. At this time, the holding dogs T U permit the wire or band to slip idly below the lips *h* of the anchor blocks under the strain of the pulling heads, but said dogs T U prevent any backward slipping of the wire or band, and thus preclude relaxation of the tension placed on said band. The operator pulls on lever O until the band is placed under such tension as may be determined sufficient by the operator, there being no practical limit to the tension up to the breaking strain on the wire or band. The lever O and heads K L having been turned the required distance, and the dogs T U being in gripping engagement with the band, the operator now moves the lever O in a reverse direction and thus reverses the direction of the rotation of the pulling heads K L, at which time the dogs P P' permit the shoul-
dered part of the wire to slip between them, and the bevel *q* of the stop Q allows one extremity of the wire to slide over the stop, whereas the other extremity of the wire slips out of the notch *l'* of pulling head L and moves idly past the dog R, the positions of the parts and of the wire ends being shown in dotted lines in Figures 3 and 5, when the pulling heads and lever are returned to normal positions. The lever O having been moved back to a horizontal position rear-
wardly of the machine, the operator now presses down on lever O to steady the machine, and pulls upwardly and forwardly on lever I', the result of which is to rotate gear I and twister pinion C, the latter acting to twist together the parallel parts of the wire and produce the twists *x*² on the looped band *x* shown in Figure 12. As the looped band is closed by twisting together its ends, by a forward movement of lever I', the studs *j'* on the gear I are brought forward by the rotation of the gear I, and at the proper time said studs *j'* ride on the cutters J J for rocking them on their pivots and thus operating said cutters to sever surplus material from the looped band. The band is cut at points close to the twist so as to leave no protruding wire ends, and by cutting the surplus material from the loop the machine is cut loose so that it may be shoved away from the loop X, which is tightly applied to the package.

The operations of training a wire or band around the package and of manipulating the machine are performed rapidly and easily by the workman. The wire or band is applied tightly and its ends securely locked and sealed. The machine is light in weight to enable it to be carried easily from one place to the other, and as the workman is able to use two hands in operating the machine, a day's work of strapping boxes is accomplished without undue fatigue on the part of the workman.

Having thus fully described the invention,

what I claim as new and desire to secure by Letters Patent is:

1. Tension means for a package strapping machine including a plurality of rotatable heads, band-gripping means comprising a plurality of separately pivoted gripping members and a single gripping member co-operating with a fixed member engageable automatically with the respective end portions of a looped band, said band-gripping means being carried by said rotatable heads for applying tension to the band loop by pulling on the respective end portions of said band, and rotatable means for directing the end portions of said band into position for engagement by said band-gripping means. 70 75 80

2. In a tension device, a movable head, a band-gripping device movable therewith adapted to grip the band on insertion therein and stopping means secured to said head and also movable therewith for limiting the insertion of a band with respect to said head and the gripping device. 85

3. In a tension device, a movable head, a band-gripping device movable therewith adapted to grip the band on insertion therein, and stopping means carried by the head and also movable therewith and positioned in the path of a band for engagement therewith. 90 95

4. In a tension device, a rotatable head, a band-gripper carried by said head, and a stopping device carried by the head and positioned adjacent to the band-gripper so as to lie in the path of a band adapted to be engaged by said band-gripper. 100

5. In a tension device, a rotatable head, gripper means carried thereby, a band-directing member separate from said head, around which a band is adapted to be bent, and a band-stopping device positioned to limit sidewise movement of a band with respect to said gripper means when said band is deflected into contact with the band-directing member. 110

6. In a tension device, a rotatable head, band-gripping means carried by said head, band-directing means, and band-stopping means, secured to said head and co-operable with said gripping means and directing means. 115

7. In a tension device, a rotatable head, band-gripping means thereon, and band-stopping means positioned for an end portion of a band to slip past said stopping means when the rotatable head is rotated in one direction. 120

8. In a tension device, a rotatable head, band-gripping means, and band-stopping means positioned in the path of a band when inserted into engagement with said gripping means, said stopping means being provided with a deflecting face over which the extremity of the band is adapted to slide when said head is turned in one direction. 125 130

9. In a tension device, a rotatable head, provided with means for the attachment of a band, a band-gripper pivoted to said head for movement therewith, said band-gripper operating in conjunction with the head to hold a band when the head is rotated in one direction and said gripper being releasable when the head is turned in a reverse direction, and band-stopping means carried by the head for movement therewith, said band-stopping means being in co-operative relation to the band-gripper.

10. In a tension device, a rotatable head, a band-gripper rotatable therewith and operable to grip a band when the head is turned in one direction, means for releasing said gripper from a band upon a reverse movement of the gripper with the head, and band-stopping means in operative relation to the band-gripper for arresting the extent to which a band is inserted into said band-gripper.

11. In a tension device, a rotatable head, a band-gripper pivoted thereto, and a releasing member positioned in the path of the gripper and operable to shift the latter from engagement with a band upon the return of the head and the gripper to normal.

12. In a tension device, anchor blocks provided with band-directing projections, band-directing sheaves mounted adjacent said projections, means for tensioning a band, and band-holding members movably attached to the anchor blocks for co-operation with said projections.

13. In a tension device, anchor blocks provided with a fixed member and carrying a movable member co-operable with said fixed member for holding a band against relaxation of tension thereon, said fixed member being in overhanging relation to the movable member and said fixed member and the movable member being co-operable with each other in directing a band in a definite path to a tension means, combined with means for placing tension on the band.

14. In a tension device, anchor blocks provided with fixed band holding members, movable band holding members co-operable with said fixed members, and directing sheaves mounted on the anchor blocks, in combination with tension members movable relatively to said band holding members for pulling a band to place tension thereon.

15. Tension means for a package banding machine embodying a plurality of pulling heads rotatable concurrently for pulling the respective end portions of a looped band, and a plurality of grippers separately pivoted to one of said heads for engagement with one end portion of the looped band, said grippers being relatively positioned for the opposing faces thereof to produce an intervening space the width of which exceeds the normal diameter of the band.

16. Tension means for a package banding machine embodying a plurality of heads rotatable concurrently for pulling on the respective end portions of a looped band, and a plurality of grippers pivoted independently of each other to one of said heads and rotatable therewith, said plurality of grippers being movable relatively to each other and said grippers being provided with gripping faces related to each other to produce a tapering space the width at one end of which space exceeds the normal diameter of the band.

17. Tension means for a package banding machine embodying a plurality of heads movable arcuatively and concurrently for pulling the respective end portions of a looped band, and a gripper carried by one of said heads, said gripper including a plurality of band-engaging members separately pivoted to said one head and said pivoted members being relatively movable for introduction of a band end between them.

18. In a tension device for package bands, a pulling head, an automatic band gripper movable therewith, and a band stopping device positioned in co-operative relation to the band gripper.

In testimony whereof I have hereto signed my name this 28 day of April, 1924.

SPENCER C. CARY.
